UNITED STATES PATENT OFFICE.

WILLIAM H. PARRY, OF KENOSHA, WISCONSIN, ASSIGNOR TO SIMMONS COMPANY, OF KENOSHA, WISCONSIN, A CORPORATION OF DELAWARE.

FOLDING CHAIR.

Application filed May 4, 1921. Serial No. 486,760.

To all whom it may concern:

Be it known that I, WILLIAM H. PARRY, a citizen of the United States, residing at Kenosha, in the county of Kenosha and State 5 of Wisconsin, have invented certain new and useful Improvements in Folding Chairs, of which the following is a specification.

My invention has reference more particularly to a chair of the type in which the seat and back and supporting legs fold together in a flat compact structure.

The principal objects of my invention are to provide an improved folding chair; to 15 simplify and improve the connections whereby the chair back and seat are mounted on the side supports; to afford improved mechanism for effecting a simultaneous folding and unfolding of the chair seat and leg support; and in general to produce a 20 folding chair which is better constructed and more satisfactory than chairs of this character heretofore provided.

On the drawings, Fig. 1 is a side view 25 of the chair unfolded and ready for use;

Fig. 2 a side view of the folded chair;

Fig. 3 a view looking at the left of the structure of Fig. 2, with portions broken away to disclose details of construction; and 30 Fig. 4 a fragmentary sectional view on the line 4—4 of Fig. 2.

On the drawings, the reference numerals 1 indicate spaced legs or side supports which are extended upwardly to serve as back posts, and have their upper ends connected together by a strip 2. A chair seat 3 is positioned between the supports 1 and provided at each side with a hanger comprising an elongated plate 4 which is secured to the edge of the seat 3 and has an offset ear 5 intermediate of its ends which is pivoted to the adjacent support 1 as indicated at 6. Extending upwardly from a point adjacent the rear edge of the seat 3 is the chair back 7 which has a bracket 8 secured to the lower end of each side thereof, and formed with a forwardly curved extremity which is pivoted to the rear end of the corresponding plate 4, the curvature of the bracket 8 being sufficient to offset the pivotal connection 9 of the chair seat with the back so that the seat and back fold close together in parallel relation as shown by dotted lines in Fig. 2.

55 In view of the fact that the connection 9

of the chair back with the seat 3 is eccentrically disposed from the pivot 6 of the seat, a sliding connection is required between the upper end of the chair back and the posts 1. To afford such connection, a pin 10 is 60 secured to and extends inwardly from each post 1 and has the inner end thereof engaged in a slot 11 formed in the edge of the chair back 7, said pin being formed with an enlarged intermediate portion 12 which 65 serves as a spacer to hold the chair back and side supports 1 in the proper separated relation.

Extending between the side members 1 below the seat 3 is a rung 13 which has the 70 ends secured to the members 1. A pair of leg supports 14 are pivoted intermediate of their ends on the reduced extremities of the rung 13, being connected together by the rungs 15 and adapted to open outwardly to 75 the position shown in Fig. 1 so that the seat 3 rests upon the upper extremities thereof, and these leg supports are also adapted to fold in between the side members 1 as shown in Fig. 2.

For effecting a simultaneous folding and unfolding of the seat 3 and leg supports 14, there is a link 16 at each side of the chair, each of which has one end pivoted to the chair seat 3 as indicated at 17, and the 85 other end pivoted to the adjacent leg support 14, as indicated at 18, the length of the link 16 and the position of the pivots 17 and 18 being such that when the seat 3 is swung on its pivots up between 90 the supports 1, the links 16 draw the leg supports up between the side supports 1 and contact with the out-turned portions of the ears 5 to limit the folding movement of the 95 chair and avoid improper unfolding movement of the chair.

While I have shown and described my invention in a preferred form, I am aware that various changes and modifications may be made without departing from the principles of my invention, the scope of which is to be determined by the appended claims.

I claim as my invention:

1. In a folding chair, the combination 105 of crossed and pivoted legs, the outer ones of which are extended to constitute the back posts, a seat having an offset bracket pivoted to the outer legs, a chair back pivoted to the seat and slidably connected at its upper end with the back posts so that the 110

seat and back fold together between the back posts beyond the upper end of the inner pivoted legs, and a link pivoted at one end to the seat and at the other end to an inner leg so that they fold and unfold simultaneously, the offset portion of the aforesaid bracket being adapted in the folded position to serve as a stop against which the link engages.

10 2. In a folding chair, the combination of crossed and pivoted legs, the outer ones of which are extended to constitute back posts, a seat having laterally offset ears adjacent the rear end pivoted to the outer legs so as 15 to fold between the latter beyond the upper ends of the inner legs, a chair back slidably connected at its upper end to the back posts and pivotally connected at its lower end to the seat, said sliding connection 20 comprising a slot in the upper end of the chair back and a spacer having stems at opposite sides thereof, one of which is fixed in the upper end of the back post and the other of which slidably engages in the slot 25 of the chairback and means connecting the

seat and the inner legs so that they fold and unfold simultaneously.

3. In a folding chair, the combination of crossed and pivoted legs, the outer ones of which are extended to constitute back posts, 30 a seat having brackets on the opposite side edges with laterally and upwardly offset ears adjacent the rear end pivotally connected with the outer legs so that the seat folds between the latter beyond the upper 35 ends of the inner pivoted legs, a chair back having a pair of offset brackets at the lower end pivoted to the seat, means slidably connecting the upper end of the chair back with the back posts and a link at each 40 side of the seat having one end pivoted to the seat and the other end pivoted to the corresponding inner leg so that the seat and the inner legs fold and unfold simultaneously, said links being laterally offset 45 between the ends so as to straddle the brackets on the edges of the seat and engage the offset portions of said brackets in the folded position.

WILLIAM H. PARRY.
